ANIMATED SIGN

Glenn A. Rogers, Los Angeles, Calif., assignor, by
mesne assignments, to The Magnalite Corporation,
Los Angeles, Calif., a corporation of California

Application February 2, 1935, Serial No. 4,656
Renewed August 30, 1937

5 Claims. (Cl. 40—133)

This invention relates to illuminated signs wherein the representation of some picture, letter, figure, insignia or other device is caused to appear upon a suitable member by the projection of light through properly arranged perforations in said member. In order to enhance the effect, beads or other transparent, refractive elements, usually of various colors, are secured within the perforations and the light is projected through them. The differently colored beads are preferably small so that intricate designs may be shown, and the colors are so arranged as to produce the best artistic effect. In particular, the invention relates to what has been termed animated signs, in which the rays of light passing through the beads are interrupted in such a manner and with such frequency as to give the appearance of ripples or wavelets of light. This attracts the attention of the by-passers by reason not only of its animation but of its striking beauty. The interruptions of the rays of light are effected by moving a suitably perforated plate transversely across the rays between the light-source and the member carrying the beads. To produce the best effect, the perforated plate should be given a non-linear motion. In the drawing, I have shown two structures for effecting such motion. In one, the plate is circular and is rotated about a central axis. In the other, it is carried upon two or more parallel crank-pins, as will be fully described. These structures are shown for illustrative purposes, and it is understood that other arrangements of the plate and other mountings and movements thereof may be adopted to give the desired effects without departure from my invention. Further, the details shown and described may be varied. It is not intended, therefore, that the claims hereof be limited to the arrangements of the parts and to the details of structure shown any farther than their specific terms make necessary.

The perforated plate, or animator as it is herein termed, and the source of light are within a closed casing or cabinet, of which the front wall is the member carrying the beads. The animator is parallel to and closely adjacent said front wall. In that structure in which the animator is mounted upon the crank-shafts, any suitable type of electric motor may be employed for revolving the crank-pins. In the other and, for some reasons the preferred structure, the animator is the rotor of the motor.

In the drawing, Fig. 1 is a rear view of a part of a sign having the rear wall removed, showing one type of animator, a portion of which is bro-

ken away to disclose a design on the face-plate; Fig. 2 is a section taken on the line 2—2 of Fig. 1; Fig. 3 is a vertical sectional view through the back-plate showing the lamp and mirrors thereon; Fig. 4 is an end view of one of the magnet poles, showing the so-called teaser mounted thereon; Fig. 5 is a section on the line 5—5 of Fig. 4; Fig. 6 is a side elevation of a motor used in one form of my invention, a part of the animator being indicated in broken lines, and Fig. 7 is a sectional view taken vertically through the center of the magnet in Fig. 6.

Referring first to Figs. 1, 2 and 3, 10 and 11 represent, respectively, the front and the rear walls of the casing or cabinet within which the movable members of the sign are enclosed. The top, bottom and side walls are designated 12. The front wall is referred to herein as the face-plate. It is provided with closely spaced perforations within which are the beads or other glass-like elements 13, the same being arranged to form the design, emblem or other character which is to be displayed. In Fig. 1, the design is a simple star, which is shown in outline only. Often-times in practice the design comprises considerable areas which are filled with the beads so closely spaced as to give the appearance of a continuous or solid surface, and the beads may be of various colors, if desired. The face-plate may be made of any suitable material. If the sign be intended for such uses as subject it to dampness or other destructive conditions, it is preferably made of sheet-metal and coated with a suitable varnish, enamel or other substance. Likewise, the other walls may be made of any suitable material and so coated. Near the rear wall is a source of light such as an electric lamp 14. But one lamp is shown, but it is to be understood that others may be employed if found desirable or necessary for the proper distribution of light over the design on the face plate. Such distribution may be furthered by the use of a frosted lamp bulb and by the application thereto of a patch of aluminum paint, as shown at 14a. The inner surface of the back-plate is preferably polished or otherwise treated to make it a reflector. Mirrors 15 may also be employed to help distribute the light. As shown, both the lamp and the mirrors are mounted on the back-plate, but they may be supported from any other suitable part of the sign structure. The mirrors are preferably adjustable angularly, like the rear-view mirrors in automobiles.

Closely adjacent the inner surface of the front-plate 10 and parallel thereto is a disk 16 which

is herein termed the animator. From its center projects a rearwardly-extending shaft 17, which is journaled in a bearing 18 on the upper end of a standard 19 which is shown as supported upon the bottom wall of the casing, although it is obvious that it may be attached to any of the walls 12. The animator is thus adapted to rotate with the shaft 17 turning in its bearing; or the shaft may be dispensed with and the bearing member 18 be made solid with the animator turning about its end. The precise nature of the mounting for the animator is not material, it being merely necessary to have the animator centrally held for rotation.

15 The animator is provided with concentric rows of perforations throughout that part which is parallel with the face-plate 10. The perforations 20 of the outer row are relatively large; but those of the other rows diminish in size progressively as 20 the rows approach the center. Moreover, the perforations in one row are staggered with respect to those of the adjacent rows, as shown. If this arrangement of diminishing sizes of perforations were carried out to the center of the animator, the 25 perforations of the inner rows would be too small. As will be seen, therefore, the perforations of the inner rows are larger than they would have been if the arrangement described had been carried through to the center of the animator. As nearly 30 as possible, the sizes and arrangement of the perforations should be such as to give a uniform illumination over the entire design on the face-plate.

35 The animator is preferably of aluminum having a gauge of from 28 to 30. If it were thinner than that, the metal would tend to buckle, whereas, if it were of a thicker gauge it would not only be unnecessarily heavy and harder to turn but would interfere with the diffusion of the light. 40 I have discovered that if the animator is too thick, the light falls upon the face-plate in spots while if it be made of the thin gauge specified the light is much better diffused. Further, the animator should be spaced from the face-plate 45 from one-fourth to three eighths of an inch, while the source of light should be not less than six and one-half inches from the face-plate.

Various kinds of driving means could be employed for rotating the animator, but I prefer 50 the simple structure shown, wherein the animator is the rotor element of an induction motor. To better adapt it for that purpose, it is provided with a flange 16a which extends rearwardly from about its outer edge. Preferably, this flange is 55 integral with the animator 16. It can be formed by simply spinning the aluminum disk from which the animator is made. The flange 16a extends between the poles 21 of an electro-magnet, the coils for which are shown at 22 and the yoke at 60 23. Preferably, the magnet is positioned at one corner of the casing as otherwise the outer pole would necessitate a smaller animator. As shown particularly in Figs. 4 and 5, a portion of the adjacent faces of each of the magnet poles is 65 covered with a so-called teaser 24, the same comprising one or more plates of non-magnetizable metal, preferably copper. These plates are shown as semi-circular disks so as to cover half of the face of the magnet, to the pole of which they are suitably but rigidly attached, as by a 70 screw 25. In order that the spaces between the teasers and the rotor flange 16a may be as narrow as practicable, the heads of the screws 25 are preferably countersunk into the outer faces of the teasers, as shown.

The magnet may be held in position by any suitable means, as by a bracket 26. Since in a rectangularly-shaped casing or cabinet the most ample space outside the flange 16a of the animator is at the corners, I prefer to place the 5 magnet at one of the latter, adjacent which the bracket is attached. The bracket is angular, having a part which is extended at a right angle to the magnet yoke 23. The outer pole piece 21 is shouldered at 27 where it abuts against the yoke, 10 and is provided with an extension 28 which extends through an aperture in the yoke and is adapted to turn therein. A shouldered screw 29 extends through the bracket 26 and is threaded 15 into the pole piece, the shoulder abutting against the end of the latter so that the screw may be set very tightly without clamping the bracket. Preferably, a suitable washer 30 surrounds the shouldered part of the screw between the bracket and the screw-head. With such a structure, the screw 20 may be turned in the bracket, thus to turn the pole piece and the teaser 24 thereon. The upper pole-piece is, by a similar structure, made rotatable in the upper end of the yoke. In order that the lower screw 29 may be reached by a screw 25 driver, the corner of the casing or cabinet is preferably beveled and an aperture 31 is formed therein through which the screw-driver may be projected. As is obvious, the flange 16a may be omitted to leave a flat circular disk for the animator. In such case, the magnet poles would be horizontal on opposite sides of the disk and no aperture in the casing would be necessary for inserting a screw driver.

It will be understood, of course, that the magnet, as well as the electric lamp, will be suitably wired for connection with a source of alternating current, and that rapidly alternating fields of magnetic lines of force will pass between the pole-pieces and through the rotor-flange 16a. 40 Thus will electro-magnetic forces be set up which may be utilized to turn the rotor in either direction desired and at variable speeds. The changes in direction and speed are effected by turning the pole-pieces and the teasers 24. When the teasers 45 are in the position shown in Fig. 1, the rotor will be turned in one direction at its maximum speed. If the teasers be turned through 180°, the rotor will be rotated in the opposite direction at its maximum speed. When turned but half way, or 50 through 90°, the forces acting upon the rotor are so balanced as to neutralize one another, and the rotor will stop. When turned in either direction from the neutral position the rotor will turn in a direction dependent upon the direction the teasers 55 have been turned and at a speed dependent upon the angle through which they have been turned until the maximum speed has been attained. By thus regulating the direction and speed of the rotor, the desired lighting effects may be secured.

It is obvious that rotors or animators of any desired size may be employed. One having a large diameter will, of course, be heavier and somewhat harder to turn than one with a small diameter. 65 But this disadvantage with the increase of size is offset by the fact that the forces which effect the rotation are applied at the outer edge of the rotor and the larger the diameter the greater the radius or lever through which the force acts. 70

In Fig. 6 I have shown a modified structure in which the animator is not rotated about a central axis but is so moved that every part of it is caused to travel in a relatively small circular orbit. This is effected by mounting the ani- 75

motor, the outline of which is indicated at 31a, upon parallel crank-pins 32 which project from cranks 33 secured to parallel shafts 34 and 35. These shafts are provided with gears, 36 and 37 respectively, of the same size, which are connected by an idler gear 38. The shafts are thus rotated at the same speeds and in the same direction and the crank-pins move together and describe equal circles. The animator, being carried by these pins, is moved bodily and every part of it is carried through a circular orbit of the same diameter as the orbits of the crank-pins. The animator is preferably a rectangular aluminum plate with rows of perforations therein, its 10 perforations of one row being staggered with respect to those of the adjacent rows. The spacing of the animator from the front plate, its thickness, and the distance from the light source to the face-plate are as set forth with reference 15 to the form first described, but the perforations are preferably all of the same size. In practice I have found it desirable to make the diameter of the perforations $\frac{1}{4}$ inch and the distance between their centers $\frac{3}{8}$ of an inch.

25 In Fig. 6, the shafts 34 and 35 are journaled in suitable standards 39 which project from a base-plate 40. The electro-magnet is substantially the same as that of Fig. 2, but the yoke 23a lies flat upon the base plate to which it is 30 suitably secured. The pole-pieces, not shown, extend horizontally and are turned through adjusting screws 29a for the purpose described. The rotor, 41, is a plain flat disk of aluminum which is secured to a shaft 42 that is journaled in brackets 43, the latter being supported in any suitable way, as from the magnet yoke. On the shaft 42 is a pinion 44 which is geared with the gear wheel 36. As will be understood, when the direction of rotation of the rotor is reversed by turning the screws 29a and the teasers, the direction 40 of rotation of the cranks is likewise reversed so that the perforations in the animator are turned backwardly in their orbits.

Having thus described my invention, I claim:
45 1. A device of the character described comprising a shaft, a plain metallic disk secured to said shaft, alternating - current electro - magnetic means for acting inductively upon said disk to rotate it and said shaft, an animating member consisting of a flat plate with perforations therein, a plurality of cranks having pins upon which 50 said member is supported, and gearing connect-

ing said shaft with the said cranks to revolve the crank-pins in orbits, whereby the animating member is moved bodily in such manner as to cause the perforations therein to move in orbits having the same diameters as the orbits of the 5 crank-pins.

2. A device of the character described, comprising a shaft, a metallic disk secured to said shaft, alternating - current electro - magnetic means arranged to act inductively upon said disk to rotate it and said shaft, an animating member consisting of a flat plate with perforations therein, a plurality of pins to which said member is connected and through which it is moved, a pinion attached to said shaft, and gears 10 connected with said pinion and with said pins whereby the rotation of said gears causes the pins to move in circular orbits and the animating member to be moved bodily in such a manner that the perforations therein describe circles 15 having the same diameters as the orbits of said pins.

3. A device as set forth in claim 2 having means for regulating the inductive action of the electro-magnetic means whereby the speed of rotation of the disk may be varied.

4. A device of the character described comprising a shaft, means for rotating said shaft, an animating member consisting of a flat plate with perforations therein, a plurality of cranks 30 having pins upon which said member is supported, and gearing connecting said shaft with the said cranks to revolve the crank pins in orbits, whereby the animating member is moved bodily in such manner as to cause the perforations 35 therein to move in orbits having the same diameters as the orbits of the crank pins.

5. A device of the character described, comprising a shaft, means for rotating said shaft, an animating member consisting of a flat plate 40 with perforations therein, a plurality of pins to which said member is connected and through which it is moved, a pinion attached to said shaft, and gears connected with said pinion and with said pins, whereby the rotation of said gears 45 causes the pins to move in circular orbits and the animating member to be moved bodily in such a manner that the perforations therein describe circles having the same diameters as the orbits of said pins.

50 GLENN A. ROGERS.
